UNITED STATES PATENT OFFICE.

ELMER N. STACY, OF MINNEAPOLIS, MINNESOTA, ASSIGNOR TO DECARIE INCINERATOR COMPANY, OF MINNEAPOLIS, MINNESOTA, A CORPORATION OF MINNESOTA.

INCINERATOR.

1,114,199.

Specification of Letters Patent.

Patented Oct. 20, 1914.

Application filed September 27, 1913. Serial No. 792,117.

To all whom it may concern:

Be it known that I, ELMER N. STACY, a citizen of the United States, and a resident of Minneapolis, Hennepin county, Minnesota, have invented certain new and useful Improvements in Incinerators, of which the following is a specification.

The object of my invention is to provide an apparatus in which refuse and garbage may be placed and consumed.

A further object is to provide an improved form of garbage grate, which will allow the flames to pass in and around the mass of garbage, thereby effectually drying same and hastening the consumption.

Other objects of the invention will appear from the following detailed description.

The invention consists generally in various constructions and combinations, all as hereinafter described and particularly pointed out in the claims.

In the accompanying drawings forming part of this specification, Figure 1 is a vertical, sectional view through an incinerator embodying my invention, Fig. 2 is a similar view, taken on a section line at right angles substantially to the section line of Fig. 1.

In the drawing, 2 represents the wall of the incinerator, having a water leg or circulating chamber 3 extending around and through the side walls and over the top of the combustion chamber 4. This chamber has a flue 5 leading to the stack and a pipe 6 in the top through which refuse from an upper floor may be discharged into the combustion chamber. An opening 7 is provided in the front wall of the chamber, having a charging door 8. Beneath this charging door is a firing door 9 adjacent to the fuel grate 10 supported on brackets 11 in the lower part of the combustion chamber above the ash pit 12. This ash pit has the usual door 13 leading thereto.

Near the rear wall of the combustion chamber and a suitable distance above the fuel grate 10 is a header 14, preferably of extra heavy material and connected at each end with the circulating chamber 3 in the side walls of the combustion chamber. A series of stay tubes 15 lead from this header outwardly to the front wall of the combustion chamber communicating with the circulating chamber beneath and near the opening 7. These tubes form a drying grate, upon which the material to be consumed is

thrown. They are inclined downwardly and inwardly from the front wall of the combustion chamber to the header and the material deposited on these tubes has a tendency to slide inwardly toward the header. A series of similar tubes 16 lead from the top of the header and communicate with the circulating chamber in the top of the combustion chamber. These tubes 16 are spaced from the rear wall of the combustion chamber so that the flames from the burning fuel on the grate 10 may pass up between these tubes and the wall of the combustion chamber and circulate in and around the mass of refuse or garbage supported by the tubes 15 and the header 14. I have found that this arrangement will insure a more complete combustion of the garbage than where it is allowed to lie in direct contact with the outside walls of the combustion chamber. Furthermore, a large area of the circulating tubes is exposed to the flames of the burning fuel and the water will be more quickly heated and the steam more rapidly generated. The wall of the combustion chamber is preferably inclosed in a suitable asbestos covering 17.

In various ways the details of construction herein shown and described may be modified and still be within the scope of my invention.

I claim as my invention:

1. An incinerator comprising a combustion chamber having water circulating chambers in its walls and a fuel grate in the lower part of said chamber, a header arranged horizontally near the rear wall of said combustion chamber above said grate and communicating with said outer circulating chamber, circulating tubes extending vertically from said header to the water circulating chamber in the top of said combustion chamber, and similar tubes extending forwardly and upwardly from said header to the front wall of said combustion chamber and also communicating with said water circulating chamber.

2. An incinerator comprising walls having water circulating chambers therein, and a combustion chamber provided with a fuel grate, a header extending transversely of said combustion chamber above said fuel grate and near the rear wall of said combustion chamber, and circulating tubes lead-

ing from said header and communicating with said water circulating chambers in the front wall of said combustion chamber, said tubes forming an inwardly and downwardly inclined drying grate, and the front wall of said combustion chamber having a filling opening above said drying grate.

3. An incinerator comprising a combustion chamber having water-circulating chambers in its walls and a fuel grate in the lower part of said chamber, a comparatively large header pipe extending transversely of said combustion chamber near the rear wall thereof and adjacent to said fuel grate and having its ends connected to said circulating chambers, a series of circulating pipes extending upwardly from said header pipe and communicating with said circulating

chambers in the top of said incinerator, a series of circulating tubes extending upwardly from said header pipe to the circulating chamber in the top of said incinerator, a series of similar tubes extending from said header pipe upwardly and forwardly to the circulating chamber in the front wall of said incinerator, said incinerator having a filling opening above and near the outer portion of said last named tubes, and a fuel supply door beneath said tubes.

In witness whereof I have hereunto set my hand this 20th day of August 1913.

ELMER N. STACY.
